UNITED STATES PATENT OFFICE

JULIUS EHmann, OF NEWARK, NEW JERSEY

EYELASH AND EYEBROW COLORER

Application filed April 8, 1929. Serial No. 353,317.

It is common to apply coloring matter to the eyelashes and eyebrows to make them stand out more distinctly and enhance their beauty, and the coloring matter commonly employed is preferably of two shades—black or brown—to correspond with the color of the hair of the individual.

In applying the coloring matter, extreme care must be exercised, because if incorrectly applied, it will detract rather than enhance the appearance.

It is an object of my invention to provide a device for applying coloring matter to eyelashes or eyebrows, which is so constructed as to conform to the configuration of the parts to be colored and is adapted to apply the coloring matter rapidly and accurately, without injury.

A further object of my invention is to produce a device of this character, which is easy to manipulate, is composed of essentially few parts, and is susceptible of rapid and economical manufacture from any suitable metal by the use of simple tools and dies.

These and other advantages, which will later appear, are accomplished by the simple and practical construction and arrangement of parts hereinafter described and exhibited in the accompanying drawings, and in which:

Figure 1 represents a perspective view of my improved device.

Figure 2 represents a side elevational view of the same, showing its application to the face, shown in dotted lines.

Figure 3 represents a front elevational view of the handle jaw.

Figure 4 represents a perspective view of the color-receiving element, preferably in the form of a rubber tube.

Figure 5 represents a top plan view of my improved device.

As shown in the drawings, my device consists essentially of the handles or tongs 1 and 2, pivotally secured together at 3, provided at their lower ends, with finger-receiving elements 4, and at their upper ends with suitable jaws 5 designed to receive color applicators 6, preferably in the form of pieces of soft rubber tube. The jaws 5 are

provided with integral extensions preferably curved to conform to the configuration or outline of the parts to be colored and the integral extensions are separated by the gap 7 so that the color applicators 6 may be secured thereon as clearly illustrated in Figures 2 and 5.

The coloring matter is preferably placed on the high portions of the inner or opposed surfaces of the applicators 6, and in operation, the handles 1 and 2 are drawn together to clamp the eyebrows or lashes between the tubes 6, causing the coloring matter to spread over the eyebrows or lashes.

After coloring one of the eyelashes, it is merely necessary to reverse the device so that the curved portion of the jaws will conform to the configuration of the opposite eyelashes.

The device is highly sanitary for the reason that the color applicators 6 may be readily removed for cleaning and replacement.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. A device for applying coloring matter to hair comprising tong members pivoted together, a fork on each tong member, the fork being provided with elements directed toward but short of each other, providing a gap therebetween, and resilient members mounted on the fork elements and bridging the gap.

2. A device for applying coloring matter to hair, comprising two tong members pivoted together, a fork on each tong member, the fork being provided with elements directed towards but being short of each other, providing a gap therebetween, and resilient members inserted on the fork elements through the gap therebetween and bridging the gap.

This specification signed this 1st day of April, 1929.

JULIUS EHmann. 100
